UNITED STATES PATENT OFFICE.

WILLIAM PARRY, OF CROWN POINT, INDIANA.

PORTABLE BURIAL-VAULT.

No. 823,893.

Specification of Letters Patent.

Patented June 19, 1906.

Application filed December 7, 1905. Serial No. 290,805.

To all whom it may concern:

Be it known that I, WILLIAM PARRY, a citizen of the United States, and a resident of Crown Point, in the county of Lake and 5 State of Indiana, have invented certain new and useful Improvements in Portable Burial-Vaults, of which the following is a specification.

My invention is in the nature of an improved portable concrete burial-vault or sarcophagus adapted to receive a casket.

It is designed to secure a thoroughly dry receptacle for a body buried in wet ground or quicksands.

15 The object is not so much to make a vault impervious to the percolation of water through its walls, (since all concrete vaults are more or less porous,) but rather to take care of such percolation by providing means 20 whereby any accumulation of water may be allowed to escape by suitable drainage and the ingress of such accumulations prevented from rising to the casket by a pneumatic cushion of gas maintained in the vault and 25 around the casket and which serves to resist the entrance of water into the casket in case the water should gain access to the interior of the vault.

30 My invention consists in a vault made of cement concrete in which the two side walls and two end walls are made integral without any joints or seams and with the bottom and top open, forming a four-walled integral curb and having a recessed inner edge.

35 When sunk in the ground, a detachable bottom is placed within the four walls of the vault at an elevation of about eighteen inches from the bottom and sustained upon pillow-blocks of concrete in the bottom of the grave, 40 and a detachable top or cover is arranged to fit tightly the recess in the upper edges of the four side walls and is hermetically sealed by a luting of cement around the said upper edges of the side walls to maintain the air-tight 45 closure of the casket to enable it to act as a pneumatic caisson, as hereinafter described.

Figure 1 is a perspective view of my improved burial-vault with a portion of its side walls broken away to expose the interior. 50 Fig. 2 is a cross-section taken on the line 2 2 of Fig. 1.

In the drawings, V V' V² V² represent the four side walls of my improved burial-vault, which are integrally formed by being molded 55 between suitable collapsible forms or mold-sections. These side walls are made of the

best Portland cement, and in the four right angles of the corners are embedded suitable angle-irons G to give stability to the vault, so as to permit it to be moved from place to place. This portion of the vault serves to act as a curb when sinking it in wet ground, as hereinafter described.

The bottom of the vault is formed of a separable section P, which may also be made of cement or of stone, closely fitted to the side walls of the vault. This bottom is sustained at an elevation of about eighteen inches above the lower edge of the side and end walls of the curb, so as to leave a considerable space below said bottom for the accumulation of any water which may gain access to the vault.

M M are pillow-blocks of cement concrete arranged transversely in the grave below the level of the bottom P and extending down to the level of the lower edges of the side walls of the curb.

Upon the detachable platform P is sustained the casket X.

The upper edges of the side walls are recessed or rabbeted at L on the inner side to form a seat to receive the detachable top T, composed of a slab of concrete or any other suitable material, and the groove formed 85 between the edges of this top T and the edges of the side walls is to be filled with a suitable luting of cement, so as to form a hermetically-sealed joint resolving the vault after the casket is sealed therein into a tightly-inclosed 90 caisson.

In making use of my vault in wet ground or quicksand the excavation for the vault is started a little larger than the vault. After water begins to appear the curb portion V V' 95 V² V² of the vault is lowered into the excavation. The grave-digger then gets inside this curb and continues to throw out the dirt from the open bottom of this curb, the curb gradually sinking in the soft ground as this digging proceeds until the proper depth has been attained. The pillow-blocks M M are then placed inside the grave, the casket-supporting bottom P is placed on the pillow-blocks, the casket lowered thereupon, and the cover T is then put on and tightly luted 100 down with cement.

Before closing the cover T down upon the side walls of the curb any suitable chemical is placed within the chamber of the vault 110 above the platform, which chemical is designed by gradual decomposition to produce

a filling of gas in and around the casket within the vault and generates a pneumatic pressure within the vault, which tends to force outwardly all liquids which may find their way into the vault. After the cover T has been tightly luted down this pneumatic cushion within the vault generates a long-continued pressure that forces outwardly all water or other liquids and prevents them from rising to the level of contact with the casket. If desired, the chemical selected may be incorporated with or composed of suitable antiseptics to contribute to the preservation of the body.

15 Various receptacles may be placed within the vault outside of the casket to hold the chemicals used to generate the pneumatic cushion. These may be in the nature of small gas-generators, or a simple vase, such as 20 I have shown at Z, may in some cases be sufficient with slowly-decomposing chemicals.

I am aware that vaults and caskets have been made of cement in various forms and that a tight covering (having closed sides, 25 ends, and top) has been placed over a casket, like an inverted bell-jar, to trap a cushion of air and hold back the access of water from a casket resting on elevated supports in a grave, and I do not claim this broadly. My invention 30 is distinctive, in that my vault has its two sides and two ends integrally formed without joints and has an open top and bottom, so as to permit a man to stand in the same and throw out the wet earth or quicksand while 35 the heavy vault slowly settles down to its full depth. For this purpose the lower edges of the walls should be sufficiently thin to permit the walls to settle down—*i. e.*, there should be no broad base at the bottom edges of the 40 walls, but the latter are made of uniform thickness from top to bottom to facilitate downward movement. My invention operates on the principle of a coffer-dam or well-

curb while excavation is in process, and when the cover is tightly cemented on it forms then 45 a tight caisson, which hermetically incloses the casket and holds back the approach of water to the casket.

If the interval between sinking of the curb and the insertion of the casket is so 50 great as to allow the water to rise in the curb, it is to be bailed or pumped out immediately before lowering the casket, and after the casket is inserted and the top luted down with a hermetically-sealed joint the pneumatic 55 pressure within, increased by the generation of gases, will keep the water-level always below the bottom P on which the casket rests.

Having thus described my invention, what I claim as new, and desire to secure by Letters Patent, is—

1. A burial-vault consisting of a coffer-dam or curb portion whose sides and ends are integrally constructed of cement, but with open top and bottom, the walls of the same 65 being made perpendicular and of uniform thickness and having along the inner side of its upper edge a continuous recess and a detachable cover fitting this recess and adapted to be hermetically sealed therein. 70

2. A burial-vault consisting of a coffer-dam or curb portion whose sides and ends are integrally constructed of cement but with open top and bottom, the walls of the same 75 being made perpendicular and of uniform thickness and having along the inner side of the upper edge a continuous recess, a detachable cover fitting this recess, pillow-blocks arranged within the bottom of the enclosure and a platform mounted on the pillow-blocks. 80
